UNITED STATES PATENT OFFICE.

HARRY E. BROOKBY, OF EVANSTON, ILLINOIS.

PARALLEL-CURRENT CALCINING-KILN.

1,390,335.

Specification of Letters Patent. Patented Sept. 13, 1921.

Application filed March 10, 1919. Serial No. 281,772.

To all whom it may concern:

Be it known that I, HARRY E. BROOKBY, a citizen of the United States, residing at Evanston, in the county of Cook and State 5 of Illinois, have invented a certain new and useful Improvement in Parallel-Current Calcining-Kilns, of which the following is a specification.

My invention relates to common direction 10 or parallel current calcining kilns, and the object of the invention is to provide a kiln so constructed that high initial temperatures may be employed, so as to reduce the time of heat treatment to a minimum and yet make 15 it possible to so accurately control and distribute the heat as to avoid volatilization or fusion of substances in the charges that are easily volatilized or easily fused. To illustrate, in Patent Number 1,297,078, granted to me March 11, 1919, I have described a 20 process for obtaining a water soluble potassium compound from hydrous, potassium bearing silicates, and it is important in that process to avoid the volatilization of any 25 appreciable amount of the potassium compound. For commercial reasons it is desirable to fire the kiln with powdered coal instead of employing liquid or gaseous fuel. But powdered coal requires quite a high 30 temperature to properly maintain combustion, viz., about 1500° C. whereas in the process mentioned the temperature at which 35 the reaction should take place (and to which it must be limited during the reactive period if the process is to be efficiently carried out) 40 is much lower than this. My purpose is to make it possible to deal with high initial temperatures, and specifically to use powdered coal as fuel, and at the same time make it possible to efficiently practice processes having heat limitations such as typified 45 in the process described in my said patent.

Other objects of the invention are to provide means for completing the heat treatment effectively and in a minimum period 50 of time and with a minimum amount of fuel; to render the process continuous; to make it possible for the apparatus to remain long in service without requiring repairs; and to facilitate inspection and repairs when necessary.

I accomplish my objects by the apparatus illustrated in the accompanying drawings in which—

55 Figure 1 is a longitudinal vertical section

of the complete apparatus omitting the lower or far end of the kiln proper.

Fig. 2 is a transverse sectional elevation on the line 2—2, Fig. 1.

Like numerals denote like parts in both 60 views.

In the form selected to illustrate the invention, the kiln proper consists of a shell comprising a cylindrical metallic case 1 and a lining 2 of fire brick or other refractory 65 material. The shell is supported so as to be able to rotate about its longitudinal axis, it being sufficient for the present purpose to show but one of the supports, which consists of an annular track 3 encircling the 70 shell and running upon a flanged roller 4 journaled in a bearing 5 mounted upon a pedestal 6. The axis of the shell is tilted downward from the head or receiving end, and suitable means (not shown) are provided for rotating the shell about its longitudinal axis. 75

In this art it is common to employ the term "counter current kilns" for those in which the gases move in one direction and 80 the charge moves in the opposite direction. Where the gases and the charge move through the kiln in the same direction, the apparatus is referred to as a "parallel current kiln." My apparatus is a parallel current kiln. 85

The head end of the shell is closed by a non-rotary hood 8 which has an annular flange 9 inclosing and making a running fit 90 with the shell. The hood consists of refractory material and is mounted upon a truck frame 10 having four flanged wheels 11, 11 adapted to travel upon rails 12, 12 arranged longitudinally of the kiln. The rails are mounted upon a suitable foundation or pedestal 13 and the construction and arrangement are such that when repairs are necessary the entire hood with the parts carried thereby (presently to be described) may be drawn back from the head end of the 100 shell a distance sufficient to afford access thereto. 95

By preference holes 14 are placed in the hood to afford means for introducing secondary air, also to facilitate inspection. 105

The hood has a comparatively large opening near the bottom into which fits a combustion chamber 15. By preference this consists of a cylindrical metallic casing 16 having a lining 17 of refractory material. 110

While the dimensions may of course be varied, in a kiln whose shell is about 6 feet in diameter the combustion chamber may appropriately be approximately 3 feet in diameter and 6 feet long and extend about 2 feet more or less into the shell. Although the combustion chamber makes a comparatively tight fit in the hood 8, it is desirable to afford it sufficient play to enable it to be 10 rotated by hand about its longitudinal axis occasionally—for example, once every day or so to equalize the wear.

Fuel, preferably in the form of powdered coal, is introduced into the combustion chamber through the head 19 thereof, by means of a pipe 20. Peep holes 22 are formed in the head of the combustion chamber, these being normally closed by suitable plugs 23.

20 The material which is to be heat treated is introduced into the kiln by a continuous feed apparatus consisting preferably of a worm or screw 26 working in a cylindrical casing 27 and mounted upon a shaft 28 driven by 25 a pulley 29. The material is fed into the casing 27 by a hopper 31 which in the best form is mounted upon and removable in unison with the casing 27. Said casing is supported by the hood 8 of the kiln with the result that when the hood is withdrawn from 30 the end of the kiln both the feed mechanism and the combustion chamber 15 move with it. A storage bin 35 is supported in fixed 35 position by stationary beams 36, 36 or other suitable supports. The flow of material from the bin to the hopper is controlled by a shut-off valve 37 of any suitable design.

The casing 27 extends a short distance into the shell of the kiln, preferably for a 40 distance of 6 to 12 inches. Secured to shaft 28 and spaced a few inches from the inner end of casing 27 is a deflector 40. This deflector has rotating vanes or paddles which brush aside, from off the top of the combustion chamber, the material which would otherwise tend to collect there.

In operation, the shell 1, 2 of the kiln is started rotating and the supply of fuel turned on. When powdered coal is used, as 50 particularly contemplated in my apparatus, combustion is started in chamber 15 by withdrawing one of the plugs 23 and inserting an igniting torch. After combustion has thus been maintained by the torch for a period sufficient to cause the walls of the combustion chamber to become heated, the combustion will be maintained automatically and the torch may be withdrawn and the plug replaced. As soon as the valve 37 is 55 slid to open position, the material to be heat treated will enter the hopper 31 and be directed by it into the casing 27 of the screw conveyer. The screw is rotated continuously and hence the process is continuous.

As above stated, to insure maintenance of 65 combustion of powdered coal, a temperature in the neighborhood of 1500° C. must be maintained, which temperature would tend to volatilize and fuse many substances and thus interfere with the proper carrying on 70 of such processes as I have above referred to. But with my apparatus the combustion chamber is long enough to enable the gaseous contents to acquire a more or less uniform 75 temperature throughout their volume before they leave the combustion chamber. Furthermore, the cold material falling upon the outside of the combustion chamber tends to cool it slightly, thus reducing the temperature of the emerging gases somewhat 80 below the highest temperature in the chamber. The result is that by this arrangement the cold material is introduced at the side of the entering blast and the temperature of the blast tends to be reduced somewhat and 85 the temperature of the cold material raised somewhat before the gases and the charge come into contact with each other. Another advantage in thus introducing the material at the side of the blast is that it eliminates 90 dust losses. Due to handling, some of the material becomes powdered by the time it leaves the feed mechanism. By keeping this away from the blast it prevents the blast from blowing the powder or dust out 95 through the kiln. In my apparatus also, the preheating period—that is, the period during which the material is being raised to the temperature at which the reaction will occur, occurs in that portion of the kiln 100 which is hottest; and the critical portion of the process occurs in those parts of the kiln which are relatively cooler and where the temperatures may be more accurately controlled.

I bring the inner end of the combustion chamber a considerable distance in through the hood and bathe the surface of the combustion chamber, so to speak, with the incoming material which is to be treated. 105 Such operation causes the temperature of the gases of combustion to be reduced somewhat before coming into contact with the charge. By the same token, the temperature of the charge is elevated somewhat, with the 110 result that it does not have to be raised so high when it does meet the gases before the reaction commences to take place. In other words, there is a tempering or equalizing of the temperatures to a certain extent before 115 the two things mingle, thus not only saving time but precluding the danger of volatilizing some of the valuable constituents of the charge.

My apparatus is therefore particularly 125 adapted for processes such as the one herein above mentioned, and in addition the process is continuous and efficient and when repairs

- become necessary access to the parts may easily be obtained by simply rolling back the hood 8 on the tracks 12. As all the operating parts except the rotating kiln itself 5 are mounted upon the hood, repairs become a comparatively simple matter, for when the hood is drawn back access is afforded to the inner end of the parts on the hood as well as to the interior of the body of the kiln.
- 10 By rotating the combustion chamber about its axis once every day or two, any wear which may occur from the constant dropping of the material onto the top of the combustion chamber may be distributed over 15 the entire inner end of the combustion chamber and hence the wear becomes practically a negligible consideration. The heat and velocity of the burning fuel passing through the combustion chamber tends to wear and 20 channel it. By rotating the combustion chamber occasionally, the wear becomes equally distributed.
- Having thus described my invention what I claim as new and desire to secure by 25 Letters Patent, is:—
1. A common direction, parallel current, calcining kiln having a rotary shell, a combustion chamber projecting into the shell, and means for introducing the charge into 30 the shell and passing it over a portion of the surface of the combustion chamber for raising the temperature of the charge and lowering the temperature of the gases of combustion before the two mingle in the shell.
  - 35 2. A common direction, parallel current calcining kiln having a rotary shell, a combustion chamber projecting into the shell, means for introducing into said combustion chamber fuel below the temperature of ignition, means for introducing the charge into 40 said shell and passing it over a portion of the surface of said combustion chamber within said shell.
  3. A common direction parallel current calcining kiln having a rotary shell, a combustion chamber projecting into the shell, and means for dropping the charge onto 45 the projecting portion of the combustion chamber.
  - 50 4. A parallel current kiln having a rotary shell provided with a hood, a cylindrical combustion chamber arranged substantially lengthwise of the shell for directing the hot gases of combustion into it, and a screw conveyor mounted in the hood and arranged parallel and adjacent to the combustion chamber for delivering a continuous charge into the shell, the delivery end of the screw conveyor being above the combustion chamber and terminating short of the delivery end thereof, so as to drop the material to be treated on to the top of the combustion chamber.
  5. A parallel current kiln having a rotary shell, a combustion chamber projecting into the shell, a continuous feed mechanism located above the combustion chamber and adapted to drop the material onto the top of it, and a deflector for brushing off the material which would otherwise tend to 70 collect on the top of the combustion chamber.
  6. A parallel current kiln having a rotary shell, a hood movable longitudinally toward and from the head end of the shell, and 75 adapted to form a closure therefor, a combustion chamber for introducing hot gases into the shell, and continuously operating means for feeding the charge into the shell, said combustion chamber and the feeding 80 means being mounted upon the hood.
  7. A common direction parallel current kiln having a cylindrical rotary shell, a hood closing the head thereof, a combustion chamber mounted in the hood and extending 85 a considerable distance into the shell from the inner face of the hood, and means for delivering the charge onto the combustion chamber at a point between the inner face of the hood and the inner end of the combustion chamber whereby the temperature of 90 the charge is raised and the temperature of the products of combustion are reduced before the two mingle in the shell.
  8. A parallel current calcining kiln having a cylindrical rotary shell, a hood closing the head end thereof, a combustion chamber extending an appreciable distance into the shell from the inner face of the hood, and a screw conveyer mounted in the 95 hood and having its inner end located above the combustion chamber and projecting about half as far into the kiln as the combustion chamber does, said combustion chamber being cylindrical, and the screw 100 conveyer being located centrally above the combustion chamber for discharging the material onto the top of it.
  9. A parallel current calcining kiln having a rotary shell, a hood forming a closure 110 for the head end of the shell, and a cylindrical combustion chamber mounted in the hood and rotatable about its longitudinal axis.
  10. A parallel current calcining kiln having a rotary shell, a hood forming a closure 115 for the head end of the shell, a cylindrical combustion chamber projecting a considerable distance into the head end of the shell, and a conveyer adapted to drop the material to be treated onto the top of the inner end of the combustion chamber, said combustion chamber being rotatable about its longitudinal axis to distribute the wear 120 caused by the dropping material.
  11. A common direction parallel current kiln having a cylindrical rotary shell, a hood closing the head thereof, a combustion 125

chamber mounted in the hood and extending a considerable distance into the shell from the inner face of the hood, means for introducing into said combustion chamber fuel below the temperature of ignition, and means for delivering the charge in an approximately continuous stream onto the combustion chamber at a point between the

inner face of the hood and the inner end of the combustion chamber and causing the 10 charge to pass down around the surface of said combustion chamber.

In witness whereof I have hereunto subscribed my name.

HARRY E. BROOKBY.
